Attorney, Agent, or Firm—Cushman, Darby & Cushman[57] **CLAIM**The ornamental design for the teacup or similar article,
as shown and described.**DESCRIPTION**FIG. 1 is a side elevational view of a teacup or similar
article showing my new design the side opposite is a
mirror image;FIG. 2 is an end elevational view taken from the left
side of FIG. 1;FIG. 3 is an end elevational view taken from the right
side of FIG. 1;

FIG. 4 is a top plan view thereof;

FIG. 5 is a bottom plan view thereof; and,

FIG. 6 is a cross-sectional view thereof taken along line
6—6 in FIG. 4.The characteristic feature of my design resides in the
single row of beads incised into the sidewall between
two elongated grooves in combination with the config-
uration of the teacup or similar article as best shown in
FIGS. 1, 2 and 3 on the drawing.
